(57) **CLAIM**

We claim the ornamental design for a terminal module, as shown and described.

DESCRIPTION

FIG. 1 is a perspective view of a terminal module according to the invention;

FIG. 2 is a right side view of the terminal module of FIG. 1;
FIG. 3 is a left side view of the terminal module of FIG. 1;
FIG. 4 is a front view of the terminal module of FIG. 1;
FIG. 5 is a rear view of the terminal module of FIG. 1;
FIG. 6 is a top view of the terminal module of FIG. 1; and,
FIG. 7 is a bottom view of the terminal module of FIG. 1.
